(57) **CLAIM**

The ornamental design for a golf shoe upper, as shown and described.

DESCRIPTION

FIG. 1 is a perspective view of the golf shoe upper showing our new design.

FIG. 2 is a heel elevational view thereof.

FIG. 3 is a toe elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The textured leather shown in broken lines in all the drawings is for illustrative purposes and does not form any portion of the present invention.

1 Claim, 3 Drawing Sheets

FIG. 4

FIG. 5
